UNITED STATES PATENT OFFICE.

WILLIAM B. DURGIN, OF CONCORD, NEW HAMPSHIRE.

DESIGN FOR A SPOON OR FORK-HANDLE.

Specification forming part of Design No. 5,071, dated July 4, 1871.

To all whom it may concern:

Be it known that I, WILLIAM B. DURGIN, of Concord, in the county of Merrimack and State of New Hampshire, have invented and produced a new and original Design to be stamped or impressed upon the Handles of Silver Spoons, Forks, and other Silverware.

The nature of my design is fully represented

in the accompanying photographic representation, to which reference is made.

I claim as my invention—

The design for forks, spoons, and silverware, as shown.

Witnesses: WM. B. DURGIN.
CHAS. C. LUND,
L. D. STEVENS.
